CLAIM

We claim the ornamental design for a base of an autonomous mobile robot, as shown and described.

DESCRIPTION

FIG. 1 is a perspective view from above of a base of an autonomous mobile robot representing an embodiment of the present invention;

FIG. 2 is a right side view of a base of an autonomous mobile robot depicted in FIG. 1;

FIG. 3 is a left side view of a base of an autonomous mobile robot depicted in FIG. 1;

FIG. 4 is a back side view of a base of an autonomous mobile robot depicted in FIG. 1;

FIG. 5 is a front-side view of a base of an autonomous mobile robot depicted in FIG. 1;

FIG. 6 is a top view of a base of an autonomous mobile robot depicted in FIG. 1;

FIG. 7 is a bottom side view of a base of an autonomous mobile robot; and,

FIG. 8 is a perspective view from below of a base of an autonomous mobile robot depicted in FIG. 1.

Dash lines are not claimed, and are included only to show details of a base of an autonomous mobile robot design in the drawings.
